United States Patent Office

Des. 199,314
Patented Oct. 6, 1964

199,314

CASE FOR A RADIATION MEASURING DEVICE OR SIMILAR ARTICLE

Edmund G. Roberge, Medford, and Joseph P. Pennimede, Danvers, Mass., assignors to Edgerton, Germeshausen & Grier, Inc., Boston, Mass., a corporation of Massachusetts

Filed Sept. 11, 1963, Ser. No. 76,561

Term of patent 14 years

(Cl. D26—1)

FIGURE 1 is an isometric view of a case for a radiation measuring device or similar article, showing our new design;

FIGURE 2 is a front elevational view, to a reduced scale;

FIGURE 3 is a top plan view, to a reduced scale;

FIGURE 4 is a side elevational view, to a reduced scale; and

FIGURE 5 is a rear elevational view thereof, to a reduced scale.

The dominant features of our new design are shown in solid lines in the drawing.

We claim:

The ornamental design for a case for a radiation measuring device, or similar article, substantially as shown and described.
